UNITED STATES PATENT OFFICE.

THOMAS W. BEHAN, OF BINGHAMTON, NEW YORK, ASSIGNOR TO THE NINETEEN HUNDRED WASHER COMPANY, INC., OF BINGHAMTON, NEW YORK, A CORPORATION OF NEW YORK.

DESIGN FOR A COMBINED CASING AND FRAME FOR A WASHING MACHINE.

Application filed March 24, 1927. Serial No. 21,315. Term of patent 14 years.

To all whom it may concern:

Be it known that I, THOMAS W. BEHAN, a citizen of the United States, residing at Binghamton, in the county of Broome and State of New York, have invented a new, original, and ornamental Design for Combined Casing and Frame for Washing Machines, of which the following is a specification, reference being had to the accompanying drawing, forming part thereof.

The figure is a perspective view of a washing machine showing my design in full lines.

The design relates to the casing and frame for a washing machine, the particular form of the wringer and the operating means therefor, all of which are shown in the drawing in dotted lines not being a necessary part of said design.

I claim:

The ornamental design for a combined casing and frame for a washing machine, as shown and described.

THOMAS W. BEHAN.
